UNITED STATES PATENT OFFICE.

FRANCIS M. F. CAZIN, OF HOBOKEN, NEW JERSEY.

ELECTRIC-INCANDESCENT-LAMP LUMINANT AND THE PROCESS OF MANUFACTURING IT.

No. 879,083.

Specification of Letters Patent.

Patented Feb. 11, 1908.

Application filed November 30, 1903. Serial No. 183,270.

To all whom it may concern:

Be it known that I, FRANCIS M. F. CAZIN, a citizen of the United States, residing at 1108 Bloomfield street, city of Hoboken, 5 Hudson county, State of New Jersey, have invented an Improvement in Electric Incandescent Lamps, of which the following is a specification relating to such lamps and the process of making them.

10 The special purpose of this present application is of the same general character and in the same line of inventive evolution, as the applications were for the sixteen patents, issued to me under Nos. 523,460, 523,461, 15 566,285, 620,640, 621,291, 621,292, 640,366, 844,778, 835,938, 786,729, 772,215, 760,849, 770,221, 770,222, 770,223, and 846,823, and as the ten other applications, yet pending, namely Nos. 732,399, 6,061, 138,084, 170,940, 20 198,564, 210,720, 210,756, 220,819, and 225,347, are. They all relate to improvements in electric incandescent lamps as well as to the methods of their manufacture or to apparatuses used in and for 25 their manufacture. And my present special purpose is to secure patent on certain modifications in my said inventions, which, although alluded to in some of my prior applications, were not there specified explicitly 30 enough and not disclosed sufficiently for formulating on the statements as made the proper claims for their protection by patent, or to secure patent for claims, which under then prevailing rules, were forced out of 35 their original application by official demand for division. And among these I have selected for this my present application those relating to the electrolytic method of filament-manufacture in some of its manifold 40 phases of applying the same, and, including the oxygenation of the surface-metal-coating of such filaments, all amounting to an actual (and not by name only) metallization of such filaments with the use preferably of the 45 metals by me specified and enumerated in my cited Patents Nos. 835,938 and 844,778. It is on that account, that the disclosures and contents in all of the above-mentioned 50 patents and applications are made a part of this application, as if they were copied therein, and for the purpose that their contents may not legally be considered, called or treated as new matter as far as this application is concerned, they being in fact matter, 55 disclosed by this applicant and prior to the

time of formulating this application by him to secure Letters Patent therefor. And in special do I so embody in this application all the contents of my prior application No. 3,061—of Jan. 24, 1900, the invention and its specification, as therein treated, having been transferred to this application in response to official action in the said case. And I refer to all of the cited patents and applications for all information required in 60 elucidating the functions of all parts used in my improved electric incandescent lamps in connection with my improved metallized (in fact and not in name only) filaments and in characterization of the functional and 65 other qualities, on which I base my selection of material for the sundry parts of my improved lamps, and in special the selection of metal for metallizing my improved filaments. And while these improved filaments 70 are all essentially the same in their main make-up, small differences in modified treatment constitute distinct phases in the product, all of which I propose to protect by 75 separate applications, as they are made the 80 subject of demands for division.

In this application I intend principally to protect the very invention, as by me disclosed in my application No. 655,312 of October 15, 1897, namely the electrolytic method 85 of filament-manufacture and the use of a core in its final longitudinal bent form as electrode. And in special do I also refer to my application of Jan. 24, 1900, No. 3,061 the subject-matter of this application having 90 been divided out of application No. 655,312 and again transferred from No. 3,061 in response to official action of those applications.

In the adjoined drawings Figures 1 to 4 I have attempted to illustrate some of the improved features in an electric incandescent lamp, as patented to me heretofore, such as the screw-shaped smaller end of the glass-base, the provision for differential cooling of glass-walls, the wide-necked glass-bulbs and 95 the way of their necks being joined etc.

Fig. 1 illustrates in the shape of a vertical section the general make-up of my improved incandescent vacuum lamps, as they were claimed in my hereabove cited patents and 100 applications. That some new and peculiar features, thus claimed, are thus shown in joint use in the same lamp, does not mean, that they may not be used, one without the other, as the requirement in special cases 110

may call for. The peculiar features thus illustrated consist in the width of the neck of both glass-bulbs to admit a rigid or imperfectly pliable luminant, which is shown to consist of a core, stiff enough to support a metallic coat or cover. The nipples in both glass-bulbs are intended to show, that the two bulbs may be singly, while by leaving an opening in the inner bulb anywhere both 10 bulbs may be simultaneously exhausted. In Fig. 1, the all-glass-base is made of two parts, permitting the handling of the original core as well as the finished luminant by means of the smaller, tubelike part of the base exclusively. Fig. 2 illustrates the use of a single bulb with a wide neck and an all-glass-base consisting of only one piece or part and the same manner, as shown in Fig. 1, to apply differential cooling to a part of the exhausted 15 glass-bulb, as well as the screw-shaped outer end of the all-glass-base and the lateral arch-way leading from an inner navel of the base to its outside to make pole-connection easy. (Compare claim 11 of my Patent No. 620,640). 20 Fig. 3. is a section on line 5—6 of Fig. 2. Fig. 4. is a section on line 9—10 of Fig. 2.

The herebelow enumerated symbols designate the therewith marked parts as there-with specified, namely: A, an inner exhausted 25 glass-bulb; B, an all-glass base-part; C, an outer exhausted glass-part; D, an accessory tubular part of the all-glass base-part; E, the luminant part of the lamp, in Fig. 1 consisting of a core and an electrolytical metal- 30 plating exclusively, in Fig. 2, consisting of core e', a plating thereof e'' and a surface coating or plating e'''; a', a nipple, the result of closing the exhausted bulb by closing the glass-exhaust-pipe while in a state of fusion; 35 a'' a'', points in the conical neck of glass-bulbs and on the conical shoulder of the all-glass-base, on which the bulb-necks are made to fit intermediately or directly; b⁶, the conical shoulder of the wider end of the all-glass-base; b⁷ b⁸, points or parts of the inner exhausted space, where on the outside differential cooling is applied, and which are parts 40 of the all-glass-base and so shaped that they form a convex reflecting surface towards the luminant of the lamp; b⁹, b⁸, perforations or 45 openings in the all-glass-base-part through which air can circulate to produce the differential cooling of the parts b⁷ b⁸ of such base-parts as faces the exhausted bulb-space, 50 their number situate in a circle around the base, not necessarily on a symmetric line or level, being determined by the requirement of such not excessive cooling; d', the powdered-glass-seal hermetically sealing the in- 55 and-out-leading wires hermetically at the points, where they pass from an exhausted space to a non-exhausted space or vice-versa; d'', the joint between B and D at the open end of D; d², the same as d''; d⁴, the one of the 60 pole-metal-caps, which fits in form closely to 65

the smaller end of the bottle-shaped all-glass-base-part, or vice-versa, and which at d³ is electrically connected with one of the in-leading wires f'; d⁵, the same as d'' and d² but also marking the circle, where the all-glass-base serves to insulate the two inleading wires from one another without the use of plaster of paris or any other insulating and adhesion-producing material; d⁶, the point, where electrical connection, through the metal-cap d⁴ is made with the current leading to or from the lamp-socket; d¹⁰, the point, where the other pole-cap is electrically connected with one of the inleading wires; d, in the one-piece glass-base the navel in the smaller base-end with the lateral arch-way for one of the inleading wires, for making the proper electrical connection without the necessity of separate insulating material, such as plaster of paris being used, such arch-way being marked n; e', a primary core for electrolytic plating; e'', the electrolytic plating thereon; e''', either an eventual other layer of plating or the oxygenation of the surface-plating; f' and f'', the inleading wires; 70 n, an arch-way for one of the inleading wires to reach the metal-cap, inclosing the small part of the all-glass-base, without coming in contact with either the other inleading wire or the other metal-cap. 80

The electrolytic or plating apparatus, being preferably used in the manufacture of my improved metallic filaments, and the manner, in which the primary filament serves therein as electrode and core in the shape intended 95 for the finished luminant,—has been shown by me first in my application No. 655,312 of October 15, 1897, out of which it had to be divided out before Patent No. 621,292 was issued on the remaining part of such application on March 14, 1899. Since then I have 100 illustrated such apparatus in the drawings of sundry later applications, to which I hereby refer, filed for the purpose of securing by patent that, which under official requirement had to be divided out of said application No. 655,312. Hence the apparatus need not be illustrated in this case, where the apparatus as such is not claimed, but being the inventor of the electrolytic method of 105 filament-making at large, applicant now desires to secure patent for such method as well as for its product. 110

I may use carbon or other practically infusible material or I may use metal as a core,— 120 and coat the same electrolytically with metal, preferably with the natural alloy osmiridium, to create the filament proper, such as patented to me as Nos. 855,938 and 844,778, though I may vary the ingredients there mentioned by 125 substituting therefor functional equivalents.

I may use a core with its metal-plating exclusively, or with a film of chemical insulation between core and metal-cover, or 130 may use a film of chemical insulation from

atmospheric reaction on the surface, such film being of any material suitable for the purpose, and may consist of a metal of but very little affinity for oxygen, such as uranium,—or may consist of a metal easily forming a solid oxid, which has the peculiar quality of efficient light-emanation, such as the rare metals and their oxids. The chemical insulation mentioned may be produced 5 exclusively by chemical reaction under electric current between core and coating, such as by me often described in my prior applications. Any reaction, which may take place between the core,—when made 10 of carbon,—and the natural alloy, iridiosmme or osmiridium or other selected metal, does as there stated, not result in autodestruction, because it amounts only to carbonization of the metal on the mutual contact-face,—which in no wise interferes with 15 the effectiveness or life of the luminant, as described.

The adjoined drawings represent in Fig. 1. a central vertical or longitudinal section of 20 one of my improved electric incandescent lamps, as manufactured in my improved process or method, and of the special kind namely, in the manufacture of which the core is first mounted by means of the in-leading wires on an inverted test-tube. Then 25 the test-tube with the core is in second manipulation placed in an electrolytic apparatus and therein connected by the free ends of the inleading wires to serve as the deposit-receiving electrode and the core including the terminals and adjoining ends of the inleading wires immersed into the electrolyte and plated, and in third manipulation the test-tube with plated luminant is then 30 inserted in the base, and in fourth manipulation one or two bulbs are mounted on the fitting shoulder of the base. The plating may as well form a part of the third manipulation as of the second-one, according to the 35 selection of using the test-tube or the smaller end of the all-glass base, with its preferably selected screw-shape, as the means holding the luminant-electrode in the plating apparatus.

50 In Fig. 2. my improved metallized filament lamp is shown with but one bulb, and the all-glass-base is shown with an insulating arch-way or tunnel serving for passing one of inleading wires to the encircling metal-cap and pole, without coming into contact with the other or central metal-cap and pole and without the use of plaster of paris or other material than the glass of the base to produce insulation between wire and caps, respectively between the two poles.

Fig. 3. represents a section of Fig. 2. on the therein indicated horizontal line 5—6 and viewed from above, showing the air-circulation holes b^a b^s as well as the navel-top d .

65 Fig. 4. represents a section of the threaded

base-part of Fig. 2. on the screw-pitch of the therein indicated line 9—10 showing the short archway or tunnel hereabove mentioned and marked n .

I have shown in Fig. 1. the iridiosmme or other metal exclusive coating deposited on a supporting core. In Fig. 2. I have shown a side of the supporting core e' and the metal-deposit e'' a third coating e''' consisting of another layer of metal or of an additional metal- 70 layer oxidized or not on its surface.

Moreover I desire to state again, that the dimensions, that I am dealing with in making up the luminant for my improved electric incandescent lamp by plating a core electrolytically with metal, are altogether extremely minute, and its component parts, elements or materials can in consequence not be otherwise represented, as far as their cross-sections are concerned, than in exaggerated 80 thicknesses, while in all other parts the drawings represent proportional dimensions, more or less approaching real sizes. The thickness of core and metal-plating cannot be measured by common means, though in 90 still so minute thickness they perform by their chemical nature perform the function to them assigned with the distinct and specific contributive quality of an electrolytic plating of being uniform, complete and inter-adhesive notwithstanding its minute thickness.

That, which I claim as my invention is:

1. The process of manufacturing the filament-shaped luminant of an electric incandescent lamp, which process consists in the following serial actions,—namely: to plate electrolytically on a core and electrode a metal-alloy, which includes some of the practically infusible and oxygenatable class of 100 metals.

2. The process of manufacturing the filament-shaped luminant of an electric incandescent lamp, which process consists in the following serial action,—namely: to electrolytically plate and metallize a carbon core and electrode with a metal-alloy and then use the thus metallized core as electrode and plate electrolytically thereon a metal-alloy of less affinity for oxygen than the metals of the 110 alloy-core.

3. The process of manufacturing the filament-shaped luminant of an electric incandescent lamp, which process consists in the following serial actions, namely: to metallize a carbon-fillet by plating the same with a metal-alloy being practically infusible and having affinity for oxygen, and then using such metallized fillet as core and electrode to electrolytically plate thereon a layer of metal 120 alloy, having less affinity for oxygen than the alloy of the metallized core, such as rare metals and then oxidizing the surface of such rare-metals.

4. In an electric incandescent lamp a fila- 130

ment-shaped luminant, which consists of a primary core-fillet, plated electrolytically with metal-alloy.

5. In an electric incandescent lamp a filament-shaped luminant, which consists of a primary core-fillet, coated with an electrolytic deposit of layers of metal-alloys.
6. In an electric incandescent lamp a filament-shaped luminant, which consists of a

primary core-fillet, coated with electrolytic 10 deposits of layers of metal-alloys, decreasing in affinity for oxygen from the core to the surface, which surface consists of rare-metals, oxidized on their exposed side.

FRANCIS M. F. CAZIN.
